CLAIM

I claim the ornamental design for the shoe horn, as shown and described.

DESCRIPTION

FIG. 1 is a top plan view of a shoe horn showing my new design;

FIG. 2 is a side elevational view thereof, the opposite side is a mirror image; and,

FIG. 3 is a perspective view with a portion upturned.

1 Claim, 1 Drawing Sheet

FIG. 1

FIG. 2

FIG. 3
